US00D529874S

(12) **United States Design Patent** (10) **Patent No.:** **US D529,874 S**
(45) **Date of Patent:** **** Oct. 10, 2006**

(54) **POWER CONTROLLER HEAT SINK**

(75) Inventors: **Keith D. Ness**, Winona, MN (US);
Theodore T. Von Arx, La Crescent,
MN (US)

(73) Assignee: **Watlow Electric Manufacturing
Company**, St. Louis, MO (US)

(**) Term: **14 Years**

(21) Appl. No.: **29/252,387**

(22) Filed: **Jan. 20, 2006**

(51) **LOC (8) Cl.** **13-03**

(52) **U.S. Cl.** **D13/179**

(58) **Field of Classification Search** D13/179;
D23/370; 165/80.3, 104.33, 121, 122, 146,
165/180, 185; 174/16.3; 257/706, 707, 718-722;

(57) **CLAIM**

The ornamental design for a power controller heat sink, as
shown and described.

DESCRIPTION

FIG. 1 is a top perspective view of the power controller heat
sink;

FIG. 2 is a bottom perspective view thereof; and,
FIG. 3 is a side view thereof.

The broken lines are included for the purpose of illustrating
environmental structure and form no part of the claimed
design.

1 Claim, 3 Drawing Sheets

FIG. 1

FIG. 2

FIG. 3
